UNITED STATES PATENT OFFICE.

RUDOLPH W. STULER, OF MCKEESPORT, PENNSYLVANIA.

FURNACE FOR HEATING METAL SHEETS AND PLATES.

Application filed April 17, 1924. Serial No. 707,084.

This invention is for a furnace for heating metal sheets or plates, and has for its principal objects to provide a furnace for this purpose wherein the sheets or packs of 5 sheets or plates may be continuously and uniformly heated with less labor and less fuel consumption than is afforded by the present day practice.

My invention may be readily understood 10 by reference to the accompanying drawings, in which:

Fig. 1 represents a longitudinal section through a furnace embodying my invention;

Fig. 2 is a horizontal section in the plane 15 of line II—II of Fig. 1;

Fig. 3 and Fig. 4 are corresponding views, respectively, of a slightly modified construction.

In the drawings, 5 designates a furnace 20 of suitable structure, having an upper longitudinally extending heating chamber 6 and a lower longitudinally extending heating chamber 7, the two chambers being connected by the vertical passage 8.

Opening into the front of the upper chamber 6 is a restricted entrance 9, and at the bottom of the lower chamber, at the same end of the furnace, is a restricted outlet passage 10. Passages 9 and 10 are only sufficiently large to permit of the ingress and 30 egress of sheets or packs without admitting any more air than is necessary.

The upper and lower chambers of the furnace are separated by horizontal wall or partition 11. The thickness of this wall will be 35 reduced to the greatest desirable minimum, as is also the height of each chamber 6 and 7.

Mounted on the bottom of chamber 6 are 40 a series of relatively closely spaced rollers or cylinders 12, having projecting shafts 13 that are suitably journaled in the furnace structure. The rolls are all revolved in the same direction by sprocket wheels 14 on the shafts 13 and sprocket chain 15. The rollers are all driven in a direction to convey a pack or a plate away from the intake door to the back of the furnace.

The last roller 12 of the series in the upper chamber is located but a short distance back from the vertical passage 8. Rearwardly of this roller is a much smaller roller 16 that is just at the top of passage 8 and below the level of the last roller 12. This 55 roller runs idly, and is so positioned that

it has the effect of tipping a pack or plate, causing it to fall edgewise down passage 8, and thus be turned over.

In the bottom of the lower chamber is a series of rollers 17, in all respects similar to rollers 12 and having shafts, sprockets 19, and a driving chain 20. The rollers 17 are rotated reversely to rollers 12, but preferably at the same speed so that they convey the packs toward the front of the furnace to 60 be discharged through outlet 10.

Rearwardly of the last roll 17 of the lower series, and in a position to be engaged by the packs falling through passage 8, are idler rolls 21.

Provision may be made for cooling all 65 of the rolls by the location of a manifold 22 at one side of the furnace and the location of a second manifold 23 at the other side of the furnace, these manifolds having 70 branches 22^a and 23^a, respectively, these branches going to the shafts of the several rolls and having a water tight but rotatable connection therewith, such joints being designated at 24. Cold water may be supplied 75 to one manifold 22, while hot water, heated in the cooling of the rolls, flows out the other manifold 23.

In the vertical passage 8, which has a rounded rear wall, there may be provided 80 a guide structure composed of two or more vertically extending curved guide bars 25 carried on upper and lower horizontal bars 26 and 27 respectively, passing through the rear wall of the furnace. These rods are 85 preferably slidably mounted in the rear wall, so that the bars 25 may be adjusted toward or from the front of the furnace. A series of notches 28 may be provided in bars 27. At 29 are angle bars or other suitable frame 90 members fixed against movement longitudinally of the furnace, and, by co-engagement of notches 28 with bars 29, the guide bars 25 may be adjustably fixed against endwise movement. Obviously, however, any other suitable means may be provided for adjustably holding bars 25 in position.

When a pack of sheets is fed from the last 95 roller 12 to roll 16, the pack is tilted downwardly. As it falls, it is guided by bars 25, and is turned over. As the lowermost edge bears against idler rollers 21, they roll the plate onto the lower conveyor rollers 17. By 100 rollers 17, the pack is carried along the furnace and discharged through opening 10. 110

Suitable burners, indicated at 30, may be provided at each side of the outlet 10 and at other suitable points along the furnace.

Outside of the furnace, on the level with the rolls 12, are feed rollers 31, driven from rolls 12, which serve to feed packs or plates delivered thereto to opening 9. A roller conveyor 32 is located at right angles to feed conveyor 31. Outside the discharge door 10 is a conveyor 33 that may extend to a rolling mill or any other suitable point.

In operation, a pack is carried by conveyor 32 onto feed conveyor 31 which feeds the pack into the upper chamber of the furnace. In passing along the upper chamber, the top of the pack is heated. Then the pack is turned over and, as it goes along the bottom of the furnace, the part of the pack that was lowermost in the upper part of the furnace is then the uppermost, so that the pack is uniformly heated throughout. The furnace, as thus designed, uniformly heats the packs, and, at the same time, has a minimum fuel consumption. Running the outgoing sheets under the incoming sheets is a great improvement in that it allows for a furnace of large capacity with a minimum length and a consequent saving of floor space.

Instead of moving the outgoing packs under the incoming ones, I may have the two chambers disposed side by side, as in Figs. 4 and 5.

In this form, the furnace structure has two longitudinally extending chambers 41 and 42 that are side by side, and separated by a partition 43. Chamber 41 has a restricted inlet opening 44 and a restricted outlet 45 at its opposite end. In the chamber are water cooled power driven rollers 46. In the other chamber, 42, in which are similar reversely driven conveyor rollers 47, is a receiving opening 48 and a discharge 49.

Between outlet 44 of chamber 41 and inlet 48 of chamber 42, is a transfer mechanism for receiving the packs from the first chamber, turning them over, and retaining them to the second chamber. Any suitable manual or automatic means may be provided for this purpose. I have illustrated the packs as emerging from outlet 45 onto roller 50, and from which they drop onto inclined cross conveyor 52. In dropping edgewise 55 onto the cross conveyor, the pack is turned over. The cross conveyor 52 discharges the pack onto an in-feed conveyor 53 that feeds the pack through opening 48 into chamber 42.

Conveyors 31^a, 32^a and 33^a, corresponding to conveyors 31, 32 and 33 of the construction shown in Figs. 1 and 2, may be provided at the front end of the furnace.

The operation of this form is the same as that of the form described in connection

with Figs. 1 and 2, except that the furnace, instead of having two chambers and a continuous passage, with means inside the furnace for turning the packs, has means for turning the packs outside the furnace, between the incoming and outgoing heating chambers.

In either arrangement, the furnace is of advantage over present day methods in that it eliminates some of the labor, particularly the heater and his helper, it saves fuel over present methods, and effects more uniform heating.

I claim as my invention:

1. A pack heating furnace comprising a furnace structure having upper and lower longitudinally extending chambers therein, an input door opening into the top chamber at the front of the structure, a discharge door at the same end of the furnace opening into the bottom chamber, pack conveying means in each chamber, said upper and lower chambers being connected by a vertical passage, and idler rollers in the furnace in juxtaposition to the vertical passage. 80

2. A pack heating furnace comprising a furnace structure having upper and lower longitudinally extending chambers therein, an input door opening into the top chamber at the front of the structure, a discharge door at the same end of the furnace opening into the bottom chamber, pack conveying means in each chamber, said upper and lower chambers being connected by a vertical passage, and idler rollers in the furnace in 95 juxtaposition to the vertical passage, and vertical guides in the vertical passage.

3. A pack heating furnace comprising a furnace structure having upper and lower longitudinally extending chambers therein, an input door opening into the top chamber at the front of the structure, a discharge door at the same end of the furnace opening into the bottom chamber, pack conveying means in each chamber, said upper and lower chambers being connected by a vertical passage, idler rollers in the furnace in 100 juxtaposition to the vertical passage, vertical guides in the vertical passage, and means for adjusting said guides longitudinally of 105 the furnace.

4. A pack heating furnace comprising an integral structure having two separate heating chambers therein, disposed one above the other, a roll conveyor in each chamber, said conveyors operating in opposite directions, said furnace having an input opening at one end thereof into one of the chambers and a discharge opening at the same end thereof leading from the other chamber, and a transfer station at the ends of the two chambers remote from the input and discharge openings. 120

In testimony whereof I affix my signature.

RUDOLPH W. STULER.
